UNITED STATES PATENT OFFICE.

WALTER D. TURNQUIST, OF OGDEN, UTAH.

PORTABLE CHILD'S TOILET SEAT.

1,410,427.

Specification of Letters Patent. Patented Mar. 21, 1922.

Application filed October 25, 1919. Serial No. 333,317.

To all whom it may concern:

Be it known that I, WALTER D. TURNQUIST, a citizen of the United States, residing at Ogden, in the county of Weber and 5 State of Utah, have invented new and useful Improvements in Portable Children's Toilet Seats, of which the following is a specification.

The object of my present sole invention 10 is the provision of a sectional and foldable toilet seat for the use of a child; the said seat having the capacity of convenient portability in a package of small compass, and being adapted to be expeditiously and easily 15 unfolded and locked in a position for use, after which it may be superimposed upon an ordinary full size toilet seat.

To the attainment of the foregoing, the invention consists in the improvement as 20 hereinafter described and definitely claimed.

In the accompanying drawings, hereby made a part hereof:

Figure 1 is a plan view illustrating the seat in unfolded state and in readiness to be 25 locked so as to secure all of its sections in the same plane.

Figure 2 is a smaller view with the seat locked and ready for use.

Figure 3 is a transverse section taken in 30 the plane indicated by the line 6—6 of Figure 2, and showing the securing means.

Similar numerals of reference designate 35 corresponding parts in all of the views of the drawings.

Among other elements my novel child's 40 toilet seat comprises four sections 1, 2, 3 and 4, which may be made of wood, fiber, metal or any other material compatible with the purpose of the invention. The said sections in outline are preferably of the shape shown 45 in Figures 1 and 2, and their inner concave edges 5 are preferably, though not necessarily, beveled, as illustrated. The opposed ends of all of the sections, excepting the opposed ends of the sections 3 and 4, are con-

nected together through the medium of 50 hinges 6, there being three of the said hinges employed, and they being by preference of the flush type, as illustrated.

Connected by glue or otherwise to the under sides of the sections, are cushioning disks 7, of rubber or other suitable material.

In the free end of the section 3 are sockets 8, and carried by said free end is a grooved plate 9 of metal; the said plate straddling 55 the outer edge of the section as shown.

Carried by the free end of the section 4 are dowels 10, and also carried by the section 4 is a grooved plate 9 similar to the one before alluded to.

Straddling and slideable on the second-named grooved plate 9 and equipped with 60 tongues 11 is a locking or securing member 12. When the seat is unfolded to place all of the sections in the same plane, the locking 65 or securing member 12 is moved endwise over the first-named plate 9, when, with the assistance of the arrangement of the dowel pins 10 in the sockets 8, the sections 3 and 4 will be held against deflection with respect 70 to each other. When it is desired to fold the seat, the member 12 is slid off the first-named plate 9, and the seat is then folded into small compass, as illustrated, in which state it may 75 be conveniently carried in a small package or in a hand-bag or the like.

Having described my invention, what I claim and desire to secure by Letters-Patent, is:

The combination of sections the ends of 80 which are adapted to be opposed, straddling grooved plates on said sections at the outer edges of their ends, and a slideable locking or securing member straddling one of the plates and movable longitudinally on and 85 off the other plate and having tongues movable in the grooves of the plates.

In testimony whereof I affix my signature.

WALTER D. TURNQUIST.
